Des. 208,246
Patented Aug. 1, 1967

208,246

HANDLE FOR A SAFETY RAZOR OR THE LIKE

William R. Pomper, Highland Park, Ill.
(140 S. Dearborn St., Chicago, Ill. 60605)

Filed June 20, 1966, Ser. No. 2,735

Term of patent 14 years

(Cl. D95—3)

FIG. 1 is an elevational view of a handle for a safety razor showing my new design, the broken line showing of the razor head being for illustrative purposes only.
FIG. 2 is a bottom view thereof.

I claim:

The ornamental design for a handle for a safety razor or the like, substantially as shown and described.
